UNITED STATES PATENT OFFICE.

GEORGE DAMON, OF CRANFORD, NEW JERSEY, AND ELIAS S. PEETS, OF NEW YORK, N. Y.

STEREOTYPE-BLOCK.

SPECIFICATION forming part of Letters Patent No. 340,104, dated April 20, 1886.

Application filed January 23, 1886. Serial No. 189,449. (No model.)

To all whom it may concern:

Be it known that we, GEORGE DAMON, of Cranford, Union county, New Jersey, and ELIAS S. PEETS, of the city, county, and State of New York, have invented Improvements in Stereotype-Blocks for Holding Stereotype-Plates in Position for Printing; and we do declare the following to be a full, clear, and correct description of the same, reference being had to the accompanying drawings, making part of this specification, and to the letters of reference marked thereon, in which like parts are designated by the same letters of reference.

15 Figure 1 is a view of our invention, the stereotype-plate being shown removed from its position upon the blocks. Fig. 2 is a view of the invention, the stereotype-plate being shown in position upon the blocks.

20 The nature of the present invention relates to improvements in stereotype-plates and the blocks or furniture used to support them, as more fully set forth, and will be found to consist in improvements on the invention in this 25 class for which Letters Patent (now owned by us) were granted Marshall J. Hughes, February 25, 1873, the object of the invention being to construct a stereotype-plate and its supporting-blocks or furniture so that when 30 locked up in the chase and placed on the bed of the press for printing purposes it will be held more securely in position, and the liability to work loose will be greatly diminished.

To enable those skilled in the art to make 35 and use our invention we will describe the same.

A shows the plate employed by us, which may be a stereotype, an electrotype, or one formed from celluloid or like material. This 40 plate A is provided upon its back or under side with the flanges B B², placed about midway between the center and outer edges of the plate A. The blocks or furniture for supporting the plate A, when placed in a chase and

locked up, consist of a central block, C, made 45 in length to correspond with the distance between the flanges B B² upon the plate A. The upper ends of the blocks C are slightly rounded, as at b, and the side blocks, D D², concaved, as at c, and having their upper inner 50 sides inclined at e. These blocks D D² are made wider at their lower than upper portion, so that while the flanges B B² of the plate A are received and held between the block C and the blocks D D², the lower portions of these 55 blocks shall have their bearing against the sides of the block C. The construction of these blocks is more particularly shown in Fig. 1 of the drawings.

The operation may be thus described. The 60 plate A is placed upon the central block, C, the flanges B B² overhanging the sides of the same. The blocks D D² are then moved up in position until the upper inclined portions bear against the flanges B B², and their upper 65 portions support outer edges of the plate A and are then tightened in the chase by the quoins, furniture, or side-sticks usually employed for the purpose, their lower inner sides being brought flush with the sides of the central block, C. 73

It will be seen that by the construction of the plate A and blocks C D D², as set forth, the plate, when placed in the chase for printing purposes, will be securely held in position 75 and prevented from working loose.

Having now set forth our invention, we claim as new—

The combination of a plate, A, flanged, as at B B², with a central supporting-block, C, 80 and side locking-blocks, D D², constructed and operating substantially as and for the purpose set forth.

GEORGE DAMON.
ELIAS S. PEETS.
